UNITED STATES PATENT OFFICE.

ALEXANDER MIKLEA, OF DETROIT, MICHIGAN.

BOOT AND SHOE SOLE CONSTRUCTION.

1,247,132.

Specification of Letters Patent.

Patented Nov. 20, 1917.

Application filed November 13, 1916. Serial No. 131,079.

To all whom it may concern:

Be it known that I, ALEXANDER MIKLEA, a subject of the King of Hungary, residing at Detroit, in the county of Wayne and State 5 of Michigan, have invented certain new and useful Improvements in Boot and Shoe Sole Construction, of which the following is a specification.

This invention relates to new and useful 10 improvements in boot and shoe sole construction.

The primary object of the invention is a provision of a sole construction for boots and shoes whereby the wearing ply or surface 15 thereof is removable by the wearer so that a plurality of surface or wearing members may be provided, the same to be replaced upon the shoe according to wearing conditions.

20 A further object of the device is the provision of a shoe sole having removable heel and toe wearing sections adapted to be locked thereon in position for use and readily releasable by a single operation allowing the 25 said sections to be thereafter forcibly removed from the shoe.

A still further object is the provision of a combination sole for shoes whereby the shoe may be provided with different forms 30 of heel and toe wearing surfaces, readily interchangeable and renewable by the wearer without the aid of a shoe expert or a cobbler.

With these general objects in view and others that will appear as the nature of the 35 invention is better understood, the same consists in the novel combination and arrangement of parts hereinafter fully described, illustrated in the accompanying drawing and pointed out in the appended claims.

40 In the drawing forming a part of this application and in which like reference characters denote corresponding parts throughout the several views,

Figure 1 is a bottom plan view of a shoe 45 provided with the present device, a portion of the removable main sole section being broken away and the detachable heel section being removed.

Fig. 2 is a perspective view of the retainer adapted for mounting upon the main sole, the forward portion of the retainer being broken away,

Fig. 3 is an inverted perspective view of the inner or rear portion of the removable 55 sole section provided with a mounting mem-

ber and corresponding to the portion of the retainer shown in Fig. 2,

Fig. 4 is a perspective view of the inner face of the removable heel section detached,

Fig. 5 is a perspective view of the shoe 60 heel-detached illustrating the locking mechanism partially broken away,

Fig. 6 is a fragmentary sectional view through the opposite side portions of the instep of the shoe with the sole section in 65 its operative position, and

Figs. 7 and 8 are detailed sections taken upon line VII—VII and VIII—VIII of Fig. 2.

Referring more in detail to the drawing, 70 the present device being designed for employment with any form of boot or shoe, the same is herein illustrated in connection with a shoe 10 having a main sole 11, an instep portion 12 and a foundation heel or lift 13.

The heel 13 is provided with a locking mechanism consisting of a plate 14 suitably counter-sunk therein and secured thereto by hold-fast devices 15, either screws or nails, and having a substantially U-shaped flange 16 mounted thereon, with the open end of the flange terminating at a block 17 lying flush with and of a curvature conforming to the inner face 18 of the heel 13.

Locking pawls 19 are pivoted within the 85 flange 16 to the plate 14 as at 20, having their outer ends 21 projecting through the said flange beneath the marginal edge 22 thereof. A latch bar 23 is slidably arranged centrally through the flange 16 and block 90 17, having a lug 24 operatively engaging the inner ends 25 of the pawls 19. A spring 26 encircles the bar 23 between the lug 24 and the adjacent end of the flange 16, whereby the pawls have their ends 21 normally 95 resiliently positioned in their locking or projected arrangement, it being noted that the forward end of the bar 23 projects through the block 17 adjacent the instep 12 sufficiently to allow the same to be forced 100 rearwardly for retracting the said ends 21.

A removable heel section 27 is adapted for locking engagement upon the heel 13 and consists of a plurality of lifts or thicknesses 105 of leather 28, the inner thickness of which is provided with an arched frame 29 complementally formed with respect to the flange 16, the said frame being mounted upon a plate 30, secured between the inner 110 and the succeeding ply of the section 27 by

means of hold-fast members 31. It will be noted that the forward end of the plate 30 and the frame 29 lie flush with the rear face of a cutaway portion 32 of the inner lift 28, the section 27 being adapted for flat engagement with the heel 13 by sliding the frame 29 over the flange 16 with the cutaway portion 32 receiving and overlying the block 17, and in which operative position the locking ends 21 of the pawls 19 will seat within opposite keeper notches 33 in the frame 29.

A metallic retainer 34 is secured to the sole 11 marginally thereof, (or to the vamp 51, as shown in Fig. 6,) to the contour of which the same substantially conforms, by hold-fast members such as stitching 52, nails or screws positioned through perforations 35 in a channel 36 with which the retainer is provided. An inwardly projecting flange 37 is arranged upon the retainer 34 marginally thereof, having an interrupted portion 38 adjacent the inner edge of the instep 12, providing a plate portion 39.

A mount 40 of substantially the same form as the retainer 34 is secured to a removable sole section 41 by means of hold-fast devices arranged through perforations 42, such as stitches 53, in a receiving channel 43. A brace 54 is provided upon the retainer 34 and a similar brace 55 is carried by the mount 40, adapted to lie side by side when operatively arranged. The mount 40 has a marginal plate portion 44 conforming to the retainer flange 37 and adapted for reception therebeneath when the detachable section 41 is operatively positioned upon the sole 11, the said mount having a short length of flange 45 adjacent the rear instep end thereof adapted to receive the plate portion 39 of the retainer 34 by overlying the same positioned within the cutaway portion 38 of the retainer flange 37. It will be understood that the marginal plate portion 44 of the mount 40 and the plate portion 39 of the retainer 34 are so arranged upon the sole 11 and section 41 as to permit the insertion of the coöperating flanges, heretofore named, into interlocking engagement therewith.

A locking bolt 46 is carried by the lug 24 projecting forwardly through a slot 47 in the plate 14 and adapted to be projected through a slot 48 in the adjacent end of the retainer 34, for locking positioning within a keeper recess 49 in the adjacent edge of the plate portion 44 of the mount 40. A guide 50 is carried beneath a leather filling strip, mounted upon the instep of the sole 11, through which guide and strip the bolt 46 shiftably extends, it being understood that upon retracting the bar 23 the bolt 46 is withdrawn from the recess 19 simultaneously with disengagement of the locking ends 21 of the pawls.

A serviceable arrangement is provided whereby the shoe 10, has the heel section 27

and sole section 41 firmly maintained thereon when desired for use, but readily released by the wearer upon pressing the bar 23 so that such sections may then be removed at will. The present arrangement is believed to be the preferable embodiment of the invention, although it will be understood that minor changes will be made therein without departing from the scope of the invention as claimed.

70

What I claim as new is:—

1. A shoe-sole construction comprising in combination with the main sole and heel of a shoe, removable sole and heel sections independent of each other arranged thereon and interengaging therewith, and a unitary locking structure carried by the main heel section and operatively associated with the removable sole and heel section for retaining the same in position.

75

2. A device of the class described comprising a shoe having a main sole and a foundation heel, a flanged retainer carried by the sole, an auxiliary sole section, a mount carried by said sole section adapted for inter-engagement with the said retainer when the section is mounted upon the main sole, and tensioned locking means for said section being movable longitudinally of the shoe and carried by said heel adapted for engagement with the said mount.

80

3. A device of the class described comprising a shoe, flanged retaining members carried by the heel and sole portions thereof, supplemental heel and sole sections, inter-engaging members for said flanged members carried by said sections, and tensioned locking means for the said sections being movable longitudinally of the shoe.

85

4. In combination with a shoe having a heel, a plate carried by the said heel, a flange upon the said plate, a spring pressed latch bar arranged within the said flange, locking pawls operatively attached to said bar and having locking ends projecting through the said flange, an auxiliary heel section, and an arched frame carried by said section adapted for overlying the said flange when the section is operatively arranged upon the heel, and having keeper notches therein adapted for the reception of the said pawl ends.

90

5. In combination with a shoe having a main sole, a retainer marginally secured to the lower face of said sole, provided with an inwardly projecting flange, having an interrupted portion adjacent the instep of the shoe, a supplemental sole section substantially conforming in shape to the sole of the shoe, and a mount marginally carried by said section, having a marginal plate portion conforming to the said flange adapted for reception thereunder when the section is operatively arranged, the said mount having an inturned flange adjacent its instep

portion adapted for fitting within the interruption of the retainer flange in receiving engagement with the plate portion of the said retainer.

5 6. A shoe sole construction comprising in combination with a shoe having a vamp, a retainer marginally secured to the said vamp, a sole section, and a channeled mount carried by the said section adapted for engagement with the said retainer when the sole is operatively arranged upon the shoe.

10 7. In combination with a shoe including a main sole and heel section, removable sole and heel sections interengaging therewith and locking mechanism carried by the main heel section adapted to engage the removable shoe heel and sole for retaining the removable sole and heel in operative position.

15 8. In combination with a shoe including a main sole and heel section, removable sole and heel sections interengaging therewith, and a unitary locking structure for the removable sole and heel sections carried by the main heel section.

20 9. In combination with a shoe including a main sole and heel section, removable sole and heel sections interengaging therewith,

and tensioned locking means carried by the main heel moving longitudinally and transversely of the shoe for locking the removable sole and heel sections in position.

30 10. In combination with a shoe including main sole and heel sections, removable sole and heel sections interengaging therewith, and a unitary locking device for the removable sole and heel sections carried by the main heel section and including longitudinally and transversely moving parts, the longitudinally moving part adapted to retain the removable sole in position and the 40 transversely movable part adapted to retain the removable heel in position.

35 11. In combination with a shoe including a sole and heel section, removable sole and heel sections, and locking mechanism for retaining the removable sole and heel sections in position including longitudinally and transversely moving parts, the said movable parts each being carried by the main heel section and adapted to engage the removable 50 heel and sole sections.

In testimony whereof I affix my signature.

ALEXANDER MIKLEA.
